TAPE ACTUATED SNUBBING AND CUTTING MECHANISM

Clarence W. Vogt, Norwalk, Conn.

Application January 22, 1954, Serial No. 405,538

2 Claims. (Cl. 164—84.5)

This invention relates to devices for holding, dispensing, applying, and cutting adhesive tapes such, for example, as "cellophane" type tapes, fiber reinforced tapes, woven tapes and tapes coated with pressure-sensitive and other forms of adhesives, and more particularly to devices of this character wherein the tape itself serves as a means for gripping or snubbing the tape material and preventing further removal thereof from the roll of material carried by the device.

In my co-pending application Serial No. 396,144, filed December 4, 1953, there is described a tape holding and dispensing device having means to apply, snub and cut the tape material dispensed therefrom, the snubbing operation being effected by the spring action existing in a tongue member carried by the device and normally urging the tape material against a relatively stationary snubbing surface on the device.

In accordance with my present invention, the structure and operation of the snubbing element is such as to insure effective snubbing of the tape as a result of tension applied to the tape in a particular fashion.

More particularly, an object of this invention is to provide a device of the above character wherein the snubbing operation is occasioned by reason of tension applied to the tape during the tape cutting operation.

The foregoing and other objects are attained by the provision of a movable element that integrates the cutting and snubbing members and that moves as a result of the cutting operation in such fashion as to initiate the snubbing operation, this latter operation varying in effectiveness with the force applied to the movable element in order to cut the tape. More particularly, the invention contemplates the provision of a pivoted element that carries both the cutting and snubbing members.

In order that the invention may be more fully understood, it will now be described with reference to the accompanying drawings, wherein:

Fig. 1 is a view in side elevation, partly broken away, and illustrating one form of a device constructed in accordance with the present invention;

Fig. 2 is an enlarged fragmentary view similar to Fig. 1, showing the manner in which adhesive tape may be drawn from the tape holder;

Fig. 3 is a view similar to Fig. 2, showing the manner in which the adhesive tape is snubbed and cut after a desired quantity thereof has been withdrawn from the holder;

Fig. 4 is a plan view of a rocking or pivoted member;

Fig. 5 is a view in end elevation showing the cutting member of Fig. 4;

Fig. 6 is a view in side elevation of the member of Fig. 4;

Fig. 7 is a partial view in section, taken on the line 7—7 of Fig. 5, and looking in the direction of the arrows;

Fig. 8 is a plan view of a plurality of cutting and snubbing members shown in the relationship in which they would exist during and subsequent to manufacture;

2

Fig. 9 is a view similar to Fig. 5, showing a modified form of cutting mechanism; and

Fig. 10 is a view similar to Fig. 4, showing the modified form of cutting mechanism of Fig. 9.

With reference to the above drawings, a tape holder is shown at 11 as being formed with a central boss 12 upon which a roll of adhesive tape, such as illustrated at 13, is received. The holder 11 is provided with a peripheral wall 14 having an opening 15 through which the end 16 of the adhesive tape is adapted to pass in order that the tape may be withdrawn from the holder and dispensed when and as desired. Except for the opening 15, the tape holding cavity is completely closed. As a result, the cavity may be sealed to protect the contents by the application of a small piece of tape over the opening. The holder 11 is formed with sides 17 having extensions 18 between which a bridge or other connecting member 19 is formed. The extensions 18 include therebetween a downwardly sloping shelf 20 having, at 21, a snubbing surface that is formed adjacent the opening 15. This surface is fixed with respect to the holder and, as will be seen in Fig. 1, is adapted to be engaged by the adhesive side of the tape 16.

When the tape is positioned in the holder and not in use, it may be turned downwardly and applied to the outer side of the peripheral wall 14, as indicated at 22. During use, however, the extremity 22 of the tape extends outwardly as illustrated in Figs. 2 and 3.

In order that the tape material may be effectively cut when and as desired, and at the same time snubbed and held in a desired position with respect to the holder, the extensions 18 are provided with a rocking or pivoted member 23 having an arm 24 at the extremity of which is provided a presser pad 25 which is adapted to press the tape against the snubbing surface 21, as illustrated in Fig. 3. The arm 24 may be formed of reduced width, as indicated at 24', to permit the arm to flex somewhat so that the end 25 thereof will move upon the snubbing surface 21 and enhance the snubbing action, and also to provide clearance to permit the finger to be inserted and applied to the tape. The member 23 is provided with a notched or recessed portion 26 that is adapted to be mounted pivotally upon a pin 27 formed between the walls 18 or formed integrally with one only of these walls. The bridge 19 is formed with a confining flange 28 in order that the pivoted member 23 may be secured pivotally in the position illustrated in Figs. 1 to 3 and in such fashion that it may partake of a limited amount of rocking or pivotal motion without permitting the dislodgement of the member.

Upon the outer portion of the member 23, a V-shaped cutting element 29 is formed, the point or notch 30 of which element is located intermediate the sides of the tape and in such fashion that it will penetrate the tape 55 between the sides thereof, as illustrated in Figs. 3 and 5.

It will be seen that the cutting element 29 is partially embedded within the material of the pivoted member 23 and, in order that the piercing of the tape may be facilitated, the side portions 31 of the pivoted member 23 are cut away or tapered, as illustrated in Figs. 5 and 6. If desired, the edge of the cutting element 29 may be chamfered in either direction, for example as illustrated at 32, in order to improve its cutting properties.

In using the apparatus hereinabove described, it may be found desirable to start the application of the tape by pressing the free end 22 thereof against the desired surface. In order to facilitate this operation, the side walls or plates 18 are cut away as indicated at 33, in this fashion permitting a finger of the operator to be inserted upon the tape in order that the free end may be pressed down and held against a desired surface upon the initia-

tion of the application of tape to the surface. When a sufficient quantity of the tape has been applied and it is desired to sever the length of applied tape from the tape upon the roll 13, the holder 11 is turned in a clockwise direction as viewed in Figs. 1 and 3 and until the cutting member 29 engages the tape as illustrated in Fig. 3. Alternatively, if the holder is used in a supporting structure and thus in a relatively fixed position, the tape is moved in a counter-clockwise direction, as viewed in Fig. 1. When the tape engages the cutting member, the pivoted or movable member 23 is rocked in a counter-clockwise direction, as illustrated in Figs. 1 to 3, and the presser foot 25 is caused to press the tape against the snubbing surface 21, as illustrated in Fig. 3. In this fashion, the tape is snubbed or held against continued feeding from the holder, and further application of pressure to the holder causes the point 30 to penetrate the tape and the completion of the cut is thus made with facility. The greater the force applied through the holder, the greater will be the snubbing action, and thus the tape is automatically held or snubbed in the desired position with respect to the holder.

In manufacturing the snubber and related movable member, it is preferred to form the same by molding operations of plastic material now common in the art. The cutting member 29 is formed as a continuous element, as illustrated in Fig. 8, and is secured to the movable elements 23 in properly spaced relation to form a gang of cutting and snubbing elements which may later be separated along the regions indicated by the dot-and-dash line in Fig. 8. The extending ends may be upset or bent into any desired position, or may be severed from the body of the cutter.

Where the device is intended to be used upon relatively wide tapes or fibrous tape or tape formed of materials imparting great strength and toughness to it, the cutting element may be formed to present the sides of the V to the edges of the tape rather than to present the point 30 to the intermediate region of the tape. This is illustrated in Figs. 9 and 10 wherein the tape material 22 is illustrated as being presented to the reentrant portions of a corrugated V-shaped cutting member 34. The cutting edge of the V-shaped member may be chamfered and the V-shaped corrugated member is partly embedded within the holder 23 so that, upon turning of the holder 11, as illustrated in Fig. 3, the sides of the tape 35 are first presented to the corrugated cutter 34 (as illustrated in Fig. 9) whereupon these side edges are dragged or pulled across and down the edges of the cutter 34 to cause the tape to be cut effectively. As a result, twisting of the tape or holder is not required and the cut is formed symmetrically from the edges of the tape inwardly to the central plane thereof. In order that the material of the supporting member 23 may not interfere with this form of cutting operation, the member 23 is cut away in a generally V-shaped notch, as illustrated at 36 in Figs. 9 and 10.

While the pin 27 is shown located adjacent the cutter blade, it will be apparent that the position with respect to the cutter blade 29 and presser pad 25 may be varied. Spacing of the pin a greater distance from the cutter than that illustrated in the drawings would provide a greater snubbing force when, for example, the cutter blade becomes dull. Moreover, inasmuch as the tape is withdrawn from the roll without necessarily moving over any guide surface, the drag on the tape is reduced to zero or to a minimal amount.

I claim:

1. A tape dispensing and cutting device comprising a

frame having spaced side plates, means on said side plates for engaging and supporting a roll of tape for rotation, said plates having an interposed portion extending around a portion of the periphery of said roll and having a gap therebetween through which tape is withdrawn from said roll, an extension on said side plates to one side of said gap a pivot member mounted in said extension outwardly of the gap and to one side of the path of the tape being withdrawn through the gap, a snubbing surface on said frame adjacent to said gap and extending between said side plates, a snubbing and cutting member pivotally mounted on said pivot member for rocking movement thereon, said snubbing and cutting member having an inner end adjacent to said snubbing surface and on the opposite side of said tape from said snubbing surface, said snubbing and cutting member having an outer end on the opposite side of said pivot member from said snubbing surface and out of the path of said tape being withdrawn from said roll, a cutting element fixed to said outer end and engageable with the tape upon deflection of the latter laterally, said cutting element being a narrow V-shaped metal strip having an apex edge extending transversely of said strip and one longitudinal edge sharpened and lying in a plane to which said apex edge is substantially perpendicular, said plane of said sharpened edge being disposed substantially perpendicular to the tape approaching it from said gap, said inner end of said snubbing and cutting member being movable into engagement with said tape for pressing it against said snubbing surface upon engagement of said tape with said cutting element.

2. A tape dispensing and cutting device comprising a frame having spaced side plates, means on said side plates for engaging and supporting a roll of tape for rotation, said plates having an interposed portion extending around a portion of the periphery of said roll and having a gap therebetween through which tape is withdrawn from said roll, an extension on said side plates to one side of said gap, a pivot member mounted in said extension outwardly of the gap and to one side of the path of the tape being withdrawn through the gap, a snubbing surface on said frame adjacent to said gap and extending between said side plates, a snubbing and cutting member pivotally mounted on said pivot member for rocking movement thereon, said snubbing and cutting member being normally out of the path of said tape and having an inner end adjacent to said snubbing surface and on the opposite side of said tape from said snubbing surface, said snubbing and cutting member having an outer end on the opposite side of said pivot member from said snubbing surface and out of the path of said tape being withdrawn from said roll, a cutting element fixed to said outer end and engageable with the tape upon deflection of the latter laterally, said inner end of said snubbing and cutting member being movable into engagement with said tape for pressing it against said snubbing surface upon engagement of said tape with said cutting element.
